UNITED STATES PATENT OFFICE

ARTHUR H. WILKINS, OF PITTSBURGH, PENNSYLVANIA

PANEL WALL

Application filed May 5, 1932. Serial No. 609,394.

This invention relates broadly to walls adapted to be built up in front of rough or unfinished walls or structures in order to give a pleasant, or pleasing artistic finish. 5 Specifically, the invention relates to mausoleums, and more particularly to removable finish slabs or panels for the fronts of burial crypts and to concealed means for supporting and holding said finish slabs or 10 panels in place.

An object of this invention is the provision of a dress or finish wall that may be built up of individual slabs or panels which may be individually removed and replaced, 15 and in which the means for supporting and retaining them in place shall be concealed from view.

Another object of this invention is the provision of means whereby finish slabs or 20 panels, for the fronts of burial crypts, may be supported and removably secured in place, the slabs and said means being so constructed that, when mounted in place, the supporting and securing means shall be 25 hidden or concealed from view.

A further object of the invention is the provision of means for securing finish slabs in place, that shall be hidden or concealed from view, but which may be operated to or 30 from slab securing position from the fronts thereof.

Other objects of the invention will, in part, be apparent and will, in part, be obvious from the following description taken 35 in conjunction with the accompanying drawings in which:

Figure 1 is a fragmentary view in front elevation of a bank or section of burial crypts, some of which are closed and provided with front finish slabs, held in place by means of an embodiment of the invention, and some of which are open, the finish slab supporting and securing means, embodying the invention, being shown in full 40 lines;

Fig. 2 is a fragmentary top plan sectional view taken on line II-II of Fig. 1;

Fig. 3 is a view in vertical section of the bank or crypt taken on line III-III of 50 Fig. 1;

Fig. 4 is an enlarged fragmentary view of a front panel or slab showing a device, embodying the invention, for holding or securing a panel or slab in place, a portion of said device being broken away in order 55 to illustrate the operative relation of the component parts thereof in respect to each other and to the slab or panel;

Fig. 5 is a view in section taken on line V-V of Fig. 4; 60

Fig. 6 is an enlarged fragmentary view in section, of a front panel and crypt partition wall showing the fastening and supporting means for the panel in side elevation; and

Fig. 7 is an exploded fragmentary view, 65 in perspective, of a panel and a fastening or securing means, showing the operative relation of said means and the panel when the panel is about to be mounted in place and locked in such position by said means. 70

Throughout the drawings and the specification like reference characters indicate like parts.

In mausoleums, burial crypts are usually constructed in banks comprising horizontally and vertically aligned rows of individual crypts, each of which are separated by partition walls. The crypts also have an open end which is sealed up when a casket is 75 placed therein.

Figs. 1, 2, and 3 illustrate a bank of burial crypts 10 which are separated by vertical partition walls 11, rear end walls 12 and horizontal partition walls 13, the fronts of 80 the crypts being open.

The horizontal partition walls form the ceilings of crypts disposed in a horizontal row and the floor of the crypts immediately above the same, as is obvious from the drawings. The walls mentioned above may be 85 made of concrete or other suitable building material, concrete being the material illustrated.

When a casket has been placed in a crypt, the open front may be closed by placing a 90 slab or closure 14 across the open end thereof and cementing it in place to thereby seal the crypt. To facilitate locating, positioning and cementing the closure in place, the outer ends of the vertical and horizontal 100

crypt partition walls 11 and 13 may be recessed or undercut as at 15 to accommodate the closure, and the sealing cement or substance indicated at 16.

- 5 The recesses are preferably of such depth that the outer faces or surfaces of the closures 14 will be flush with the outer ends of the horizontal and vertical partition walls 11 and 13 (see Figs. 2 and 3).
- 10 In the interest of economy, it is preferred to make the closures or slabs 14 of concrete or rough unfinished or semi-finished material and to cover the fronts of the crypts with a false wall 17 of dress material, such as marble, or a moldable composition material having the appearance of marble. While marble, or a composition having the appearance of marble has been mentioned, it is to be understood that any material, 15 which will give a desirable and pleasing appearance, may be utilized.

In order that access may be had to the individual crypts without moving or dismantling the entire false or dress wall 17, 20 it is proposed to construct and assemble the wall from slabs or panels 18 of such size that the top, bottom and side edges thereof will lie along approximately the middle of the vertical and horizontal partition walls of 25 the crypts, and thereby conceal the sealed joints formed between closures 14 and the partition walls of the crypts. The panels 18 may be individually mounted or supported on shelves or supports 19 bolted to 30 the horizontal crypt walls and held in place by locking and retaining devices 20 and 21. Devices 20 and 21, as illustrated, are identical in construction, but have been given different reference characters for the purpose 35 of making clear that each panel is locked or retained in place by two such devices, one indicated as 20 and the other as 21. When the panels or slabs 18 are in place, devices 20 and 21 and the supports 19 are hidden or 40 concealed from view.

In order to close the spaces or joints 23 between adjacent edges of the various panels 18, removable sealing strips 24 of yieldable material, such as rubber, or cloth impregnated with rubber, may be placed between 45 the edges of the panels near the front faces thereof as shown in Figs. 5 and 6. These joints may also be closed up with cement if desired, particularly if the joints are between panels associated with crypts which are occupied and sealed up.

The supports or shelves 19 comprise short pieces of angle bar having their vertical flanges bolted to the horizontal partition 50 walls of the crypts. The finish slabs or panels 18 rest on the horizontal outwardly extending flanges of these supports 19. The horizontal flanges extend outwardly at such a distance from the crypt walls that, when 55 the panels are mounted thereon, as shown

in Fig. 6, there will be sufficient space between the panels 18 and the closures 14 to accommodate the locking and retaining devices 20 and 21. When the panels are mounted in place, only a portion of the bottom edges of the panels rest on the horizontal flanges of the supports 19 so that the sealing strips 23, or cement, if used, will conceal the supports.

The supports are so located (see Fig. 1) 75 that the corners of adjacent panels 18 may be mounted thereon.

The locking and retaining devices 20 and 21 are illustrated more particularly in Figs. 4, 5, 6, and 7. Since these devices are similarly constructed, a description of one will be sufficient for all, and similar and corresponding parts have been given the same reference characters.

With reference to Figs. 4, 5, 6, and 7, the locking and retaining devices as shown, each comprises outer stationary guide members 25 and 26, of substantially L-shape in transverse section, having therebetween a stationary spacer 27 comprising a relatively narrow strip of metal or suitable material, and a latch member 28 having a body part 29 of substantially L-shape in transverse section movably disposed between the outer guide members 25 and 26. The edge 30, of 90 the body part 29, disposed adjacent to edge 31 of strip 27 has a lug 32 adapted to engage limit stops 33 and 34 formed at the top and bottom, respectively, of the strip or spacer 27. Thus, the latch 28 may be moved upwardly between the guides 25 and 26 until lug 32 engages stop 33, or downwardly until said lug engages stop 34.

The forward edge of the latch 28 has a flange 36 disposed substantially parallel to 105 the front panels 18 adapted to be received in recesses 37 formed in the vertical edges of the front panels. An opening 39 is formed in the back face of each of the panels directly above the recesses 37, so that by raising the latches 28 until the flanges 36 are in line with openings 39, (see Figs. 4 and 7) and tilting the panels 18 to vertical position, the latches may be moved downwardly until the latch flanges 36 are in the recesses 110 of the panels (see Figs. 5 and 6). When the latch flanges are in the recesses, the slabs are locked and retained in place.

The latches 28 may be raised by merely passing a thin knife blade or similar member through the space between the adjacent panel edges, and under the latch flanges 36 and raising the blade. Each of the latches may be lowered by engaging the top of the flange 36 and pushing down on the same to 115 lower it into the associated recess of the slab or panel.

There are two devices 20 and 21 on each vertical partition wall disposed one above the other, in reverse relation to each other 120

so that one device cooperates with one panel 18 and the other device cooperates with an adjacent panel. However, in respect to each panel, the right side thereof, as seen in the 5 drawings, is engaged by a device 20, and the opposite or left side is engaged by a device 21.

The locking and retaining devices 20 and 21 are mounted on the front ends of the 10 vertical walls of the crypts and secured thereto with bolts in the relative positions indicated by the reference characters. The bolts which pass through the retaining devices, extend through the outer guide members 15 25 and 26 and the spacer strip 27, thereby holding the guide members and the spacer strip stationary but leaving the latch member 28 free to be moved up or down between the limit stops in the manner aforementioned.

In practice, the false or finish wall 17 is assembled complete from the individual panels 18 which are mounted and locked in place as described above. When a particular crypt is needed the front finish panel in front of such crypt is removed, the latches being first raised to the position indicated in Figs. 4 and 7 so as to disengage the latch flanges 36 and the recesses 37 in 20 the panels. After placing the casket in the crypt selected, the closure 14 is mounted in place and the front finish panel returned to its position and the latches returned to their locking positions as indicated in Fig. 6. 25 By inserting sealing strips, either before or after the panels have been mounted in place, in the joints between the panels, the locking and retaining devices and the supports or shelves are concealed. If the crypts have 30 been sealed up, the joints between the front finish panels for such crypts, may be cemented up if desired, to permanently seal 35 the joints.

While a preferred form and specific application for the invention have been herein shown and described, it will be apparent that various modifications and changes may be made without departing either from the spirit or the scope of the invention. It is 40 desired, therefore, that only such limitations shall be placed on the invention as are imposed by the prior art and the appended 45 claims.

What I claim as new and desire to secure 50 by Letters Patent is:

1. A wall structure comprising a plurality of horizontally disposed vertically spaced stationary supports, individual wall panels mounted on said supports, and means 55 behind said panels adapted to releasably lock and retain said panels on the supports.

2. A wall structure comprising a plurality of horizontally disposed vertically spaced stationary supports, individual wall panels 60 mounted on said supports, means behind 65

said panels adapted to releasably lock and retain said panels on the supports, and means interposed between adjacent edges of said panels to conceal the supports and the locking and retaining means from view 70 from the fronts of said panels.

3. A wall structure comprising a plurality of horizontally disposed vertically spaced stationary supports, individual wall panels mounted forwardly of and on said supports, 75 and means behind said panels adapted to coat with said panels to releasably lock and retain the panels on the supports.

4. A wall structure comprising a plurality of horizontally disposed vertically spaced stationary supports, individual wall panels mounted forwardly of and on said supports, 80 means behind said panels adapted to coat with said panels to releasably lock and retain the panels on the supports, and means 85 interposed between adjacent edges of said panels to conceal the supports and the locking and retaining means from view from the fronts of said panels.

5. The combination with an inner wall 90 having horizontally disposed vertically spaced supports extending outwardly therefrom, of an outer wall comprising a plurality of panels mounted on said supports, locking devices on said inner wall having 95 movable latches adapted to be actuated from the fronts of said panels, and means on said panels adapted to be engaged by said latches, when actuated to latching position, said 100 latches being arranged to lock and retain said panels in position on the supports.

6. The combination with an inner wall having horizontally disposed vertically spaced supports extending outwardly therefrom, of an outer wall comprising a plurality of panels mounted on said supports, devices on said inner wall having movable latches adapted to be actuated from the 105 fronts of said panels, means on said panels adapted to be engaged by said latches, when actuated to latching position, said latches being disposed to lock and retain said panels in position on the supports, and means interposed between adjacent edges of said 110 panels to conceal said supports and devices from view from the fronts of the panels.

7. The combination with an inner wall having horizontally disposed vertically spaced supports extending outwardly therefrom, of an outer wall comprising a plurality of panels mounted on said supports, locking devices on said inner wall, there being at least two devices for each panel, said devices each having a movable latch, one of 115 said devices being located behind one edge of a panel and another of said devices being located behind the opposite edge of the same panel, a latch keeper formed in each of said panel edges adapted to receive the 120 125 130

latch associated therewith, said latches being actuatable from the fronts of the panels, to and from locking positions.

8. A concealed locking and retaining device for holding wall panels in position in front of a structure to be concealed, comprising spaced stationary guides adapted to be secured to a wall and a latch movably disposed therebetween, said latch having a flange disposed outwardly from said wall and parallel to the panel, adapted to engage a recess in an edge of the panel, said flange being so shaped and positioned that it may be actuated to or from latching position by means of a tool, adapted to be inserted between adjacent panel edges, from the fronts thereof.

9. A concealed locking and retaining device for holding wall panels in position in front of a structure to be concealed, comprising spaced stationary guides secured to said walls and a latch movably disposed therebetween, said latch having a flange disposed outwardly from said wall and parallel to the panel, adapted to engage a recess in an edge of the panel, said flange being so shaped and positioned that it may be actuated to or from latching position by means of a tool adapted to be inserted between adjacent panel edges from the fronts thereof, and means for limiting the movement of said latch in respect to said guides.

In testimony whereof, I have hereunto subscribed my name this 4th day of May, 1932.

ARTHUR H. WILKINS.

CERTIFICATE OF CORRECTION.

Patent No. 1,898,026.

February 21, 1933.

ARTHUR H. WILKINS.

It is hereby certified that error appears in the printed specification of the above numbered patent requiring correction as follows: Page 4, line 1, claim 7, after "latch" insert the words "of the device"; and that the said Letters Patent should be read with this correction therein that the same may conform to the record of the case in the Patent Office.

Signed and sealed this 25th day of April, A. D. 1933.

M. J. Moore,

Acting Commissioner of Patents.
